ROY T. AXE, OF SYRACUSE, NEW YORK, ASSIGNOR TO THE Q. M. EDWARDS COMPANY,
INC., OF SYRACUSE, NEW YORK, A CORPORATION OF NEW YORK

VENTILATOR CONSTRUCTION FOR WINDOW FRAMES

Application filed September 28, 1927. Serial No. 222,654.

This invention relates to ventilators of the type used in railway cars particularly in the sill of the window frame. It has for its object such a ventilator which is built for the most part of sheet metal and hence is particularly simple and economical in construction and also a simple, efficient and reliable means for holding the ventilator in closed and different open positions which operate uniformly under all conditions.

The invention consists in the novel features and in the combinations and constructions hereinafter set forth and claimed.

In describing this invention, reference is had to the accompanying drawings in which like characters designate corresponding parts in all the views.

Figure 1 is a front elevation of this ventilator, the same being shown as applied to the sill of a window frame.

Figure 2 is an end elevation of parts seen in Figure 1, the door being shown in open position.

Figure 3 is a rear elevation, part of the frame member or sill being removed.

Figure 4 is an enlarged vertical sectional view on line 4-4 Figure 1.

Figure 5 is an enlarged fragmentary sectional view on line 5-5 Figure 1.

Figure 6 is a fragmentary plan view.

Figure 7 is a front elevation of the front plate showing the opening therein for receiving the frame which confines the ventilator opening, the frame being removed.

The ventilator comprises, generally, a door which opens and closes a door opening in the frame member as the sill of a window frame, the door being hinged at one edge, as its lower edge, and having side walls and a wall at its free or top edge telescoping into the opening of the frame member, the wall at the top edge of the door being formed with ventilator passages therethrough, and means for positively holding the door closed and in different open positions, the locking means coacting with the door between the ends thereof or remote from the ends thereof.

1 designates the frame member or sill which may be of any suitable form, size or construction. It is usually formed of sheet metal in

any suitable manner and includes a base plate 2, front plate 3 which is formed with the angular flange 4 which flange overlies the front margin of the base plate 2, a box which confines the ventilator opening 7, the box being located between the ends of the front plate.

The front margin of the bottom wall 6 of the opening 7 overlies the base plate 2 and the front margin of this bottom wall 6 is flush with portions of the flange 4 of the front plates 3 which lie on opposite sides of the door opening; it being understood that the door opening extends through the lower edge of the front plate and hence the intermediate part of the flange 4 is removed between the reference numerals 4^a as shown in Figure 1. The flange 4 and margin of base plate 2 and bottom wall 6 provides the sill member with a forwardly extending angular flange. The rear end of the bottom plate 6 is formed with the downward flange 6^a which meets the base plate 2 and it is secured thereto in any suitable manner, as by welding. The top and end walls, 7^a, 7^b of the door opening 7 provide a box like structure formed of sheet metal. The end of the opening 7 is covered by screen carrying frame 7^c.

The door 8 is also formed of sheet metal and is hinged at its lower edge by a piano hinge 9 extending the full length of the door, to a door frame fitting the front portion of the opening 7. This door frame is also formed of sheet metal and comprises the top and side members 10, 11 and a bottom member 12. The bottom member 12 is an angle iron secured at its end as by welding to the side frame members 11. The leaves of the hinge 9 are secured, as by riveting, to the upright flange of the angle iron 12. The members 10 and 11 lap the margin of the wall around the front end of the opening 7 and are provided with angular flanges 13 fitting the opening, these flanges 13 being bent to form forwardly extending channels 14 in which weather strips 15 are located. The bottom member 12 of the door frame is L shaped in cross section with horizontal flange thereof extending forwardly and overlapping the front margin of the bottom wall 6 of the door opening 7, the front margin of the bottom wall 6 occupying the

space provided by removing the intermediate part of the flange 4. The parts of the door frame are secured together usually by welding, and the door frame is secured to the frame or sill in any suitable manner as by screws 16 extending through the members 10, 11 and into the wall of the sill or frame member around the opening 7. The door 8 is formed along its top and side edges or rims with inwardly or rearwardly extending flanges 17 which enter the channels 14 and engage the weather strips therein.

The hinge 9 has one leaf overlapping the outer face of the door and its other leaf extending behind the upright flange of the lower member 12 of the door frame. The leaves are secured in position by rivets or in any other suitable manner. The door is also formed with end walls 18 and top wall 19 telescoping into the opening 7 and these are spaced apart or set in from the flange 17 and slidably fit on the opposing faces of the angular flange 13 or the parts thereof which form the channel 14. The top is formed with perforations which provide ventilating passages.

The top wall is provided with a stop shoulder 20 at its rear edge for engaging the rear side of the door frame when the door is in full open position.

The door is provided with a hand hold located on the rear side thereof, this hand hold being a plate 22 lapping the rear face of the door and having a depressed or socket portion 23 in line with a passage formed in the door. The plate is secured into position by screws 25 passing through a face plate 26 on the front side of the door and through the door and threading into the plate 22. The face plate has an opening 27 in line with the hand passage in the door.

The means for holding the door in closed and in a plurality of open positions coacts with the hand hold and is located midway between the ends of the door or in line with the hand hold. This holding means as here shown comprises a spring pressed arm 30 pivoted to a bracket 31 mounted on the bottom wall 6 of the door opening and inclining upwardly and having a roller 32 at its upper edge which coacts with the lug 33 on the hand hold. The lug is formed with a plurality of seats. The lug is shown as rectangular in form and projects rearwardly. When the door is closed the roller is seated on the upper side of the lug and when the door is open in different positions the roller seats in any one of a number of seats or recesses 34 in the rear end of the lug.

The bracket 31 comprises a base plate 35 and a pair of ears projecting upwardly from the base plate in which the pivot pin for the arm 30 is mounted; and the spring 36 is coiled about the pivot and anchored at one end thereof to one of the ears of the bracket, 55 at its other end to a pin 37 on arm 30. The

arm 30 is formed double with a roller 32 and pin 37 between the branches thereof. The base plate 35 is secured to the bottom wall 6 to the opening 3 in any suitable manner as by rivets 38.

Owing to the location of this holding means between the ends of the door or in line with the hand hold, sticking of the holding means is avoided, also the operation of the door is greatly facilitated by the coaction of the locking arm directly with the hand hold plate as the hand hold is usually a rigid casting while the remainder of the door is of sheet metal. Furthermore, owing to the location of the holding means the force applied to open or close the door, is transmitted directly through the rigid hand hold and is not affected by possible flexing of the sheet metal parts due to the door sticking in the door opening.

Owing to the construction of the door frame and the door, the door is weather tight when closed and flush with the outer face of the door frame. Furthermore, owing to the construction of the door frame it is readily applied to a frame member or window sill.

This door frame construction is furthermore particularly efficient in that it permits the major part of the structure to be formed up of sheet metal instead of castings, and is sufficiently rigid to withstand the strains to which it is submitted.

What I claim is:

1. The combination with a frame member having a ventilator opening therethrough, of a door in said opening, the door being hinged at one edge and having side walls and a wall at its free edge telescoping into said opening, the wall at the free edge being formed with ventilator passages therethrough, the door being also provided with a hand passage therethrough and a hand hold mounted on the inner side of the door provided with a depressed portion closing said opening in the door and impositive locking means for holding the door in open and closed positions, and means carried by the hand hold with which said locking means coacts to hold the door in adjusted position.

2. The combination with a frame member having a ventilator opening therethrough, of a door in said opening, the door being hinged at one edge and having side walls and a wall at its free edge telescoping into said opening, the wall at the free edge being formed with ventilator passages therethrough, the door being also provided with a hand passage therethrough and a hand hold mounted on the inner side of the door provided with a depressed portion closing said opening, the hand hold being provided with a keeper plate located near the hinged edge of the door and a spring pressed member mounted in the opening in the frame member and coacting with said keeper plate.

3. The combination with a frame member

having an opening therethrough, of a sheet metal door hinged at one edge in said opening and having walls telescoping into the opening, a stiffening member secured to the door between the ends thereof and having holder engaging means on the inner side of the door and spring pressed holder means coacting with said former means for holding the door in different angular positions, said stiffening member being formed with a hand hold exposed on the outer side of the door.

5 In testimony whereof, I have hereunto signed my name, at Syracuse, in the county of Onondaga, in the State of New York, this
10 15 27th day of September, 1927.
